UNITED STATES PATENT OFFICE.

CHARLES L. CLARKE, OF EAST ORANGE, NEW JERSEY, ASSIGNOR TO THE
TELEMETER COMPANY, OF NEW YORK.

ELECTRIC-CLOCK SYSTEM.

SPECIFICATION forming part of Letters Patent No. 367,960, dated August 9, 1887.

Application filed February 9, 1887. Serial No. 227,008. (No model.)

To all whom it may concern:

Be it known that I, CHARLES L. CLARKE, a citizen of the United States, residing in East Orange, in the county of Essex and State of New Jersey, have invented certain new and useful Improvements in Electric-Clock Systems, of which the following is a specification.

The invention relates to the organization of apparatus controlled by electric currents transmitted from more or less distant points for the purpose of indicating time.

Certain features of the invention are also applicable to the indication of temperature, atmospheric, steam, and other pressures, and to similar purposes.

The object of the invention is to provide convenient, simple, and reliable means for causing the successive impulses transmitted, to advance the indicating movement the required distance, to insure that there shall be no excess of movement, and that the apparatus shall be returned to its normal condition after each operation.

In patents granted to me October 6, 1885, Nos. 327,526 and 327,527, there are described organizations of apparatus of the same general character as that shown herein. In these patents there is shown a system of circuits and apparatus in which means are provided for placing a series of actuating electro-magnets in circuit, and for insuring that the circuit, when once closed, shall not be interrupted until all the electro-magnets have had time to perform their functions, thus guarding against any defect which might arise from the slower action of some magnets. The general plan there proposed is to place in an independent circuit an interrupting device for opening the circuit which is primarily closed. The independent circuit is completed only when the entire series of magnets have responded. With this construction, however, it may sometimes chance that by reason of a defect in some one instrument itself the electro-magnet for operating the same might fail to move its armature and complete the connections of the second circuit at that point. In such an event the primary circuit would still remain closed and the battery would be exhausted, and thus the entire system would be thrown out. The present invention is designed to overcome this

difficulty, and it is accomplished by placing in the primary circuit, in addition to the usual circuit-closer, a subsidiary circuit-controller, which will, during the greater portion of the time, interrupt the connections of the main line at a second point, but will close them before the principal circuit-closer is brought into operation, and will continue in operation until the operation of the primary circuit-closer is completed. It will then cause the primary circuit to be again interrupted after the actuated devices have had time to operate. Should, therefore, any particular actuated movement be out of order and the secondary circuit fail to be completed, the apparatus will continue to operate as a one-wire system until the defective instrument is repaired.

The accompanying drawing is a diagram illustrating the general organization of apparatus and system of circuits for carrying out the invention.

Referring to the figure, R represents a circuit-closing device applied to a moving part—say the seconds-hand arbor of a regulator. This device consists of a contact-point, r' , which is carried forward by the movements of the arbor and makes sliding contact, once each second or at any other predetermined intervals, with a contact-point, r'' . The point r'' is preferably narrow and located between two of the points of rest of the circuit-closing arm, so that by a single beat of the pendulum or movement of the balance-wheel of the clock the arm r' will be carried into and out of contact with the contact-point r'' . The circuit of a battery, O, is designed to be completed by the operation of this arm through a series of electro-magnets, M M, applied to clock-movements or other instruments, N N. The magnets M are included in a main line, L, connected at the distant station with the earth at G. At the home station this line L terminates at a contact-plate, a' , to which an arm, r^3 , moving with the point r' , is applied. A point, r^4 , upon the arm r^3 makes contact with the point or plate a' . The latter is of such width that contact will be made a certain definite time before the point r' makes contact with the point r'' , and the point r^4 remains in contact with the plate a' a certain definite time after the arm r' touches the point r'' . Thus, if the circuit is

to be closed at r^2 upon the sixtieth second, the point r^1 will touch the plate a' at the fifty-ninth second and remain in contact therewith until the end of the first second of the succeeding minute. The point r' , therefore, will always find the connections of the line L completed to itself when it is in position to make contact with the point r^2 . The connections are continued from the point r^2 by a conductor, L' , through the coils of an electro-magnet, H' , and through a lever, q^2 , applied to an electro-magnet, Q , in a manner hereinafter to be described, thence to a contact-point, q^3 , and thence to the battery O , one pole of which is connected with the earth at G' . An impulse, therefore, will be sent from the battery O through the magnets M whenever the circuit is completed at the point $r^1 r^2$.

The electro-magnet H' is provided with an armature, h , carried upon a lever, h' , and provided with a front contact-point, h^2 . The point h^2 is connected by a conductor, 1, with the conductor L' , leading to the electro-magnet, and it is designed, in connection with the lever, to form a shunt-circuit upon the points $r^1 r^2$ after the circuit is closed by the latter and the lever h' of the magnet H' has been thrown forward. For this purpose the lever is connected by a conductor, 2, with a plate, a^2 , similar to the plate a' , applied to the point r^5 , similar to the point r^1 and in electrical connection therewith. The contact of the point r^5 with its plate a^2 continues the connections to the lever h' , and when the lever h' is drawn against its point h^2 the shunt-circuit will be completed upon the points $r^1 r^2$. This circuit, it is evident, will remain complete until interrupted at the plates $a' a^2$, or else at the point q^3 .

It is the intention that the electro-magnet Q shall be vitalized after all the electro-magnets M have responded and operated their respective movements N , and thereby interrupt the circuit through the magnet H' , and thus cause a circuit to be interrupted at the point h^2 . For this purpose the lever q^2 is constructed with an extension, q' , extending into the path of the armature-lever q of the electro-magnet Q . When the magnet Q is vitalized, the lever q , striking the extension q' , lifts the lever q^2 from the point q^3 , thus breaking the circuit of the battery O . This electro-magnet Q is vitalized by a current transmitted through a second line, L^2 . This line L^2 leads from the lever q^2 through the magnet Q to the lever m^2 of the first movement N in the series. This lever is provided with a front contact-point, m' , which is connected with a section of the line L^2 leading to the lever m^2 of the next movement. This lever in turn is provided with a point m' , connected in like manner with the succeeding movement, and so on throughout the series. The last contact-point m^2 of the series is connected with the line L , leading to the earth at G^2 . When, therefore, all the levers m^2 have served to operate their respective movements, being drawn toward their electro-

magnets, the circuit of the line L^2 will be completed, the magnet Q vitalized, and the connections of both the lines L and L^2 interrupted at the point q^3 . It is evident now that should any lever m^2 fail to respond the connections of the line L^2 would remain open, and therefore the electro-magnet Q would not respond. To guard against any such failure, the device for completing the connections of the lines L and L^2 temporarily at the plates a' and a^2 is employed. By means of this device the circuit will be interrupted a moment after the impulse is sent, even though the magnet Q should fail to be vitalized, and the line will be put in condition to be again operated a second before the next impulse is to be sent. Thus the clock-movements which are in operating condition will continue to be actuated by currents transmitted over one line, L .

As it may be desired to advance the clock-movements to set them at some other time than when the plates a' and a^2 are connected through the points $r^1 r^5$, a switch, s , is employed for completing the connections between the conductor 2 and the plates a' , the latter being connected by a conductor, 3, with the switch-point s' , while the switch s is connected with the conductor 2. A key, K , connected with the point r^2 , by making contact with its point k' , will complete the circuit from the battery O through the key-lever to the conductor 2. By means of this key, therefore, as many impulses as required may be sent. A switch, M' , is included in the conductor leading from the point q^3 to the battery O , for interrupting its connections when desired.

The several electro-magnets are shown with artificial resistances t connecting their respective terminals through which the discharge takes place when the circuit is interrupted. In a patent, No. 347,572, issued to me August 17, 1886, there is shown an artificial resistance placed, as shown in the present instance, at $t' t$ in sections of the line L^2 connecting the respective movements. This is provided for equalizing the resistance of the line L^2 , for otherwise the resistance of the line L' would, if many instruments were in circuit, ultimately so far exceed that of the line L^2 as to cause the current to be immediately diverted from the line L' the moment the connections of the line L^2 were completed, thus causing the magnet H' to be demagnetized too quickly. The resistances t' are approximately equal to the resistance of the corresponding electro-magnets, M .

I claim as my invention—

1. The combination of a series of electro-magnets, devices actuated thereby, a main line including the same, a circuit-closer for completing a circuit through said main line, a second main line having its connections completed by the operation of all of said devices, a circuit-interrupting device actuated by a current through said second main line, and an independent device automatically completing connections in the first main line be-

fore and interrupting them after the operation of said circuit-closer, substantially as described.

2. The combination of a battery, two main lines deriving currents therefrom, a series of actuating devices having their actuating-magnets included in one of said main lines, a circuit-closer for said line, a circuit-interrupting device having its actuating-magnet included in the second of said main lines, means for completing the circuit of the second line when all of said devices have been actuated, and an independent automatically-operating circuit-controlling device in the first line interrupting its connections independently of said circuit-interrupting device after the operation of said circuit-closer.

3. The combination of a series of electro-magnets, a main line including the same normally interrupted at two points, means for periodically closing the connections at one point, and a device moving therewith for closing the connections at a second point before the operation of the first-named device, and causing them to remain closed at the second point until after the operation of the first-named device, substantially as described.

4. The combination of a series of electrically-actuated devices, electro-magnets for operating the same, a main line including the

electro-magnets, a moving circuit-closer, means for causing said circuit-closer to complete the connections of said main line at two different points, and causing the connections at one of the points to be of greater duration than that at the other point, and a second main line having its connections normally interrupted at each device and at a point closed by the operation of said circuit-closer, substantially as described.

5. In an electric-clock system, the combination of a series of electro-magnets, devices actuated thereby, a main line including the electro-magnets, a circuit-closer periodically completing the connections of said main line at a given point, a second main line having its connections completed when all of said devices have operated, and an automatically-operating circuit-controller normally interrupting the connections of the first-named line, except for a brief period, including the time when said circuit-closer operates.

In testimony whereof I have hereunto subscribed my name this 8th day of February, A. D. 1887.
